(57) **CLAIM**

I claim the ornamental design for a double C shaped geometric log holder, as shown and described.

DESCRIPTION

FIG. 1 is a left, front perspective view of a double C shaped geometric log holder;

FIG. 2 is a top plan view of a double C shaped geometric log holder;

FIG. 3 is a front elevational view of a double C shaped geometric log holder;

FIG. 4 is a rear elevational view of a double C shaped geometric log holder;

FIG. 5 is a bottom plan view of a double C shaped geometric log holder;

FIG. 6 is a right side elevational view of a double C shaped geometric log holder; and,

FIG. 7 is a left side elevational view of a double C shaped geometric log holder.

The surface shading represents the surface of the double C shaped geometric log holder.
